United States Patent

Des. 238,551
Patented Jan. 27, 1976

238,551

BOTTLE

Samuel J. Rivman, White Plains, N.Y., assignor to The Barcolene Company, Holbrook, Mass.

Filed May 23, 1973, Ser. No. 363,200

Term of patent 14 years

Int. Cl. D9—01

U.S. Cl. D9—43

FIG. 3

FIG. 2

FIG. 1

FIG. 4

FIG. 1 is an elevational view of a bottle showing my new design;

FIG. 2 is a plan view;

FIG. 3 is a side elevational view looking from the left of FIG. 1; and

FIG. 4 is a side elevational view looking from the right of FIG. 1.

The bottom is substantially plain and unornamented.

I claim:

The ornamental design for a bottle, as shown and described.
